CLAIM

The ornamental design for a chain restraint for a wire strainer as shown and described.

DESCRIPTION

FIG. 1 is a front perspective view of a chain restraint for a wire strainer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.
